The ornamental design for a storage device for compact discs and audio and video cassettes, as shown and described.

DESCRIPTION

FIG. 1 is a front elevational view of a storage rack for compact discs showing my new design the rear view being identical thereto;

FIG. 2 is a side elevational view, the opposite side being identical thereto; and,

FIG. 3 is a front elevational view of a modified embodiment of the storage rack for compact discs shown in FIG. 1; the rear view being identical thereto; the side views being similar to that shown in FIG. 2 except taller.

The bottom of the rack of FIGS. 1 and 3 is flat and unornamented.

FIG. 1

FIG. 2

FIG. 3
